Henry Horan Inventor

by William A. Kenyon Atty.

UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,838, dated March 28, 1882.

Application filed February 11, 1882. Term of patent 3½ years.

To all whom it may concern:

Be it known that I, HENRY HORAN, of East Orange, in the county of Essex and State of New Jersey, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

This design is for a border for a carpet; and it consists of two principal portions, A and B, above the band C, and separated by the band e, which consists of successive semi-hexagonal forms with radiating centers, the place of every fourth being taken by a four-lobed-leaf form. A consists of various leaf and flower groups traversing the background a and jutting out over the blank field b, all of which separate groups, figures, and grounds are fully described and claimed in an application filed February 23, 1882, and numbered 53,532, for a patent for a design for carpets by Julius Piegel, and which I do not therefore specifically and separately claim herein; but the particular combination of such groups, figures, and grounds herein shown is new. Below A is the band C, consisting of a series of small scalloped forms, above them a series of four-lobed-flower forms with rectangular bases, and above a series of square block forms.

D is a broad band traversed by spraying-leaf forms and broken by the vase-like forms E, which, with leaf forms springing from their sides, rise from the band e, and, spreading, support the narrow band c, composed of a row of small cup-shaped figures, and on which rests the broad band F. F includes all of the design above the band c, and consists of successive heart-shaped figures surmounted by nearly

circular flowers, and having two leaf-like forms on each side, between which springs a flat arch extending to the adjacent figures, d. Beneath the arch three circular flower forms occupy the space, each partly concealed by the band e. From the middle one rises a small spreading-flower form to the center of the arch. Above the arch are small ornamental forms, and the whole is surmounted by a line or series of small three-lobed-leaf figures, the said leaf and flower forms in part B being conventional in character.

I claim—

1. The design for a border for carpets, consisting of the figure F, substantially as shown. 55
2. The design for a border for carpets, consisting of the figure B, including the figures D E F e, substantially as shown. 60
3. The design for a border for carpets, consisting of the figures e B, including the figures D E F e, substantially as shown. 65
4. The design for a border for carpets, consisting of the figures e and B, including the figures D, E, F, and c, and the figure A, including the ground a, field b, and overlying flowers, substantially as shown. 70
5. The design for a border for carpets, consisting of the figure B, including the figures D, E, F, and c, the figure A, including the ground a, field b, and overlying flowers, and the bands C and e, substantially as shown. 75
6. The design for a border for carpets, consisting of the figures F e, substantially as shown. 75
7. The design for carpets, consisting of the figure A, including the ground a and field b, and overlying flowers, substantially as shown.

HENRY HORAN.
